UNITED STATES PATENT OFFICE.

ROBERT L. BURNS, OF TAFT, CALIFORNIA.

UNDERREAMER.

1,403,388.

Specification of Letters Patent. Patented Jan. 10, 1922.

Application filed November 29, 1920. Serial No. 426,948.

To all whom it may concern:

Be it known that I, ROBERT L. BURNS, a citizen of the United States, residing at Taft, county of Kern, State of California, have invented a new and useful Underreamer, of which the following is a specification.

This invention relates to underreamers, and is particularly directed to underreamers such as are utilized in the process of 10 drilling oil and other well bores by the reciprocatory or churn drilling method.

As is well known in this art, the well-boring or drilling tools which are employed in the reciprocatory method of drilling, only 15 drill a hole of substantially the diameter of the interior of the casing. This leaves a shoulder or annular obstruction beneath the casing which must be removed before the casing can be lowered. For this purpose 20 underreamers, provided with expandable cutters or slips, are employed, said underreamers being lowered through the casing after a period of drilling, with the slips in contracted condition. Such underreamers are 25 generally constructed so that the cutters or slips automatically expand after passing the shoe or lower end of the casing, the casing being somewhat elevated above the shoulder to permit such expansion and to permit a 30 commencement of the underreaming operation.

The present invention is directed particularly to that type of underreamer referred to in the trade as the "Bowl-type," wherein 35 the reamer body is recessed upwardly from its lower extremity providing an imperforate annular wall and a longitudinally extending cavity to receive and confine the shanks of a pair of opposed cutters or slips, the shanks 40 being movable vertically and tiltable within the body cavity to permit the slips to expand to cutting position and to be contracted from such position. In this type of underreamer it is desirable that the shanks of the 45 slips be relieved of the major portion of the strains incident to the cutting operation, that the cavity of the body be of minimum proportion so as to provide a relatively thick annular wall, and that the cooperating bearing surfaces of the wall and the slips be of such area and contour as to receive and transmit directly to the body, all strains and thrusts. At the same time the construction should be such as to avoid as far 55 as possible the formation of irregularities or pockets in the cooperating surfaces or

faces of the body and of the slips, such irregularities and pockets being difficult to form and tending to cramp and obstruct the slips and to form open spaces for the collecting 60 of sand and abrasive materials detrimental to the operation and life of the tool.

With the foregoing general requirements in view, the object of the invention is to provide an underreamer of the "Bowl" type, 65 having relatively large cooperating bearing surfaces between the slips and the body, to provide perfect seats for the slips, to provide a construction in which the wearing surfaces will to a large extent be protected 70 against the entrance of sand or other abrasive matter, and in which the major portion of the strains and thrusts incident to an underreaming operation are transmitted directly to the body.

Another object is to provide an underreamer provided with slips having cutting edges of extensive circumferential span and to provide an underreamer which will be superior in point of relative simplicity in 80 construction and organization, taken in connection with reliability in collapsing and expansion of the slips, positiveness of operation, simplicity and convenience in control and manipulation, compactness in form, durability as to the entire tool and particularly 85 as to the length of effective life of the slips and other working parts, and which will be generally superior in efficiency and serviceability.

Various other objects and advantages will be more fully apparent from the following detailed description of the accompanying drawings which form a part of this disclosure, and which illustrate a preferred 95 form of embodiment of the invention.

Of the drawings:

Figure 1 is an elevation of the underreamer of the present invention, the slips being in expanded positions.

Fig. 2 is an elevation taken at right angles to Fig. 1.

Fig. 3 is an enlarged vertical section, showing the slips in expanded positions.

Fig. 4 is an enlarged view, similar to 105 the lower end of Fig. 2, showing the body in section.

Fig. 5 is a vertical section similar to the lower portion of Fig. 3, showing the slips in collapsed position, a portion of one slip 110 being broken away to illustrate the full contour of the opposite slip.

Fig. 6 is a plan section on line X^a—X^a of Fig. 3.

Fig. 7 is a plan section on line X^b—X^b of Fig. 3.

5 Fig. 8 is a plan section on line X^c—X^c of Fig. 3.

Fig. 9 is a vertical section on line X^d—X^d of Fig. 3.

10 Fig. 10 is a bottom plan view of the body with the working parts removed.

Fig. 11 is an elevation similar to Fig. 1, showing the slips in collapsed position.

With reference to the drawings, 1 designates the body of the underreamer, and 2 the sub to which the body is joined, said sub having the usual tapered and threaded pin 3 by which the underreamer is attached to the string of tools in the usual manner. The body is recessed upwardly from its 20 lower extremity to form a substantially rectangular cavity 4 adapted to receive the respective shanks of the slips and the lower slip supporting end of the spring rod or mandrel 5. Said rod has a head 6 of rectangular cross sectional contour corresponding to the contour of the cavity 4, this preventing the rod from turning, and a circular upper portion extending upwardly through a bore in the body, said bore having an 25 enlarged upper portion providing a spring chamber 8. The upper end of the rod is screw threaded to receive the nut 9 and a coil spring 10 surrounds the rod within the spring chamber, the spring engaging the bottom wall of the chamber and a washer 30 11 beneath the nut 9.

Depending from the medial portion of the rectangular head 6 of the spring rod 5 is a flat tongue 12 carrying a transverse pivot 40 pin 13 as a means of pivotal support for the slips 14—15.

The slips 14—15 have upwardly extending flat shanks 14^a—15^a, said shanks being disposed to one side of the transverse centers 45 of their respective slips so that when assembled the shank of one slip will be positioned on one side of the tongue 12 and the shank of the opposed slip will be positioned on the opposite side thereof, each shank being pivotally journaled on an opposite end of the pivot pin 13 and the combined thicknesses 50 of the two shanks and the tongue equaling the corresponding dimension of the rectangular cavity 4, as indicated in Figs. 4 and 8.

55 Each shank, between its pivoted center and the top of its respective slip, is of a width equal to the width of the cavity 4, and above such pivoted center the side adjacent said slip is vertically angled inwardly, 60 as at 16, to permit a tilting of the slip, while the side opposite is relieved as at 17 to provide clearance against binding on the mouth of the cavity. The tongue 12 extends downwardly into clearance recess 18 in the 65 slips and has a transverse orifice 19 to ac-

commodate a suitable tool by which the spring rod may be pulled downward in setting the slips in collapsed position. The above described shank construction and pivotal connection provides slip members, 70 operating in their expanding and collapsing, with a scissor-like movement.

The contour of the lower surface of the body is of the specific configuration shown in Fig. 1, and may be formed by milling 75 straight across the lower end of the body, this providing two opposed transverse surfaces 20—20, the adjacent outwardly and downwardly angled up-thrust bearing surfaces 21—21, and the intermediate expanding lugs 22—22, there being two such lugs (see Fig. 10) by reason of the intersecting cavity 4. The lugs serve to positively expand the slips and provide opposed slip-expanding and in-thrust bearing surfaces 80 23—23, the grooves 20—20 forming out-thrust bearing surfaces 24—24 and the additional up-thrust bearing surfaces 25—25.

The upper surfaces of the slips 14—15 are contoured to closely fit the bearing surfaces of the body when in expanded position, they being provided with transverse tongues 26—26 adapted to engage within the grooves 20—20 and providing angled expanding and in-thrust bearing surfaces 95 27—27, and angled up-thrust bearing surfaces 28—28 to engage the up-thrust bearing surfaces 21—21 of the body.

The body portions of the slips are of a half cylindrical cross sectional contour providing cutting edges of extension circumferential span and the side walls of the slips are correspondingly grooved as at 30 to accommodate a retaining band or strap, as indicated in dotted lines in Fig. 5, for the purpose of holding the slip in collapsed position while the tool is being inserted into the well casing, according to a practice now well known in the art. Near their upper ends the slips have beveled shoulders 31, which when the underreamer is elevated to cause a collapse of the slips, will engage the lower end of the casing or casing shoe to hold the slips stationary while the body 1 is being drawn upwardly and cam the 100 slips inwardly to collapsed position for a withdrawal of the underreamer from the well.

From the above and with particular reference to Figs. 5 and 11 of the drawings, and considering that the spring 10 is under tension, it will be evident that when the underreamer is lowered in the well casing beyond the bottom thereof, the slips, then being free to expand, will be translated upwardly by the action of the spring 10, and by reason of the cooperative cam action of the bearing surfaces 27—23 will be positively forced outwardly during such upward movement.

When in expanded position as shown in Fig. 3 the slips have an extensive bearing against the under surface of the body and the intermeshing tongues or grooves effectively prevent a ripping out of the slips under excessive out-thrust strains. The angled disposition of the up-thrust bearing surfaces is particularly advantageous in urging the slips to close engagement with the body surfaces when subjected to up-thrust or in-thrust strains and contribute towards withstanding out-thrust strains.

The construction as above explained provides a bowl type of underreamer in which the central cavity has been reduced to a minimum diameter, leaving a thick strong bowl wall providing extensive bearing surfaces, and the slips are contoured to interlock in the grooves of the body and to provide a maximum span of cutting edge.

While the specific form of mechanism herein shown and described, is admirably adapted to fulfill the objects primarily stated, it is to be understood that it is not intended to confine the invention to the one form of embodiment herein disclosed, for it is susceptible of embodiment in various forms, all coming within the scope of the following claims.

What is claimed is follows:

1. In an underreamer, a body having an axial recess upwardly from its lower extremity forming an imperforate bowl, a spring rod slidable within said recess, a transverse pivot pin carried by the rod, a spring functioning to elevate the rod, and opposed slips having flat shanks projecting upwardly in overlapping relation and pivotally journalled on the pivot pin, the body having transverse grooves in its under surface and the slips having transverse tongues for interlocking engagement with the companion grooves.

2. In an underreamer, a body having an axial recess upwardly from its lower extremity forming an imperforate bowl, the lower face of the bowl formed to provide transverse grooves adjacent opposite sides of the recess, expanding lugs between the ends of the grooves and outwardly and downwardly extending transversely flat bearing surfaces outwardly of each groove, a rod slidable within the recess of the body, a spring functioning to elevate the rod, a pivot pin carried by the rod, opposed slips having flat shanks projecting upwardly into the recess in overlapping relation and pivotally

supported on the pivot pin, the body portion of each slip having a transverse tongue and an adjacent bearing surface adapted to engage the companion groove and bearing surface of the body on one side of the recess.

3. In an underreamer, a body provided with a recess having four vertical side walls and extending upwardly from its lower extremity to form an imperforate bowl, and an axial bore above said recess forming a spring chamber, a rod slidable in the recess and extending into the spring chamber, said rod having a head contoured to slidably fit within the recess and a flat tongue depending from the medial portion of the head and of a width substantially equal to the width of the recess, opposed slips having flat shanks extending upwardly on opposite sides of the tongue and pivotally journaled to swing thereon, the combined thicknesses of the two shanks and the tongue being substantially equal to the corresponding dimension of the recess, and a spring in the spring chamber functioning to elevate the rod, the body having means for separating the slips during their upward movement.

4. In an underreamer, a body having a substantially rectangular recess upwardly from its lower extremity forming an imperforate bowl and an axial bore enlarged at its upper end to provide a spring chamber, the lower surface of the body having transversely disposed grooves on opposite sides of the recess and formed to provide outwardly and downwardly angled bearing surfaces outwardly from said grooves, a rod slidable in the recess and bore, said rod extending upwardly into the spring chamber and having a rectangular head slidable in the recess and a flat tongue depending from said head, a spring in the spring chamber functioning to elevate the rod, and opposed slips having shanks extending upwardly into the recess on opposite sides of the tongue and pivotally connected thereto, the slips each having an upstanding transverse tongue adapted to fit into the companion groove of the body and an angled bearing surface extending outwardly and downwardly from said tongue and adapted to engage the companion bearing surface of the body.

Signed at Taft, California, this 22d day of November, 1920.
